(57) **CLAIM**

The ornamental design for an LED bulb, as shown and described.

DESCRIPTION

FIG. 1 is a perspective view of rear, bottom and left sides of an LED bulb according to a first embodiment showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a partially enlarged view at square portion 8 in FIG. 7 thereof;

FIG. 9 is a perspective view of rear, bottom and left sides of an LED bulb according to a second embodiment showing our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a partially enlarged view at square portion 16 in FIG. 15 thereof; and,

FIG. 17 is an ended view at 17-17 in FIG. 16 thereof.

The broken lines shown are included for the purpose of illustrating the unclaimed portions of an LED bulb and form no part of the claimed design.
